UNITED STATES PATENT OFFICE.

GEORGE MEGUIN, OF TREMONT, NEW YORK, ASSIGNOR TO MATTHEW J. WHITTALL, OF WORCESTER, MASSACHUSETTS.

DESIGN FOR A RUG, &c.

SPECIFICATION forming part of Design No. 20,126, dated September 2, 1890.

Application filed August 5, 1890. Serial No. 361,141. Term of patent 3½ years.

To all whom it may concern:

Be it known that I, GEORGE MEGUIN, residing at Tremont, county of New York, State of New York, have invented and produced 5 a new and original Design for a Pattern to be wrought into Wilton Rugs and other Carpets, in such coloring as may be designed; and I do hereby declare that the photographic illustration accompanying this specification 10 gives and conveys to any one skilled in the art of carpet weaving and manufacture a clear understanding of the same, and is sufficient to enable such person to use my invention.

What I claim as my invention, and desire 15 to secure by Letters Patent, is—

The design for rugs, substantially as shown in the photographic illustration accompanying this specification.

GEO. MEGUIN.
